2 Sheets-Sheet 2

UNITED STATES PATENT OFFICE.

CHARLES E. ELLIS, OF WASHINGTON, DISTRICT OF COLUMBIA, ASSIGNOR OF ONE-TENTH TO HENRY RIDDER, OF NEW YORK, N. Y.

ADDRESS PLATE AND INDEX CARD.

Application filed April 15, 1922, Serial No. 552,826.

To all whom it may concern:

Be it known that I, CHARLES E. ELLIS, a citizen of the United States, and resident of Washington, District of Columbia, have invented certain new and useful Improvements in Address Plates and Index Cards, of which the following is a specification.

This invention relates to stencil or address plates and index cards intended for use with addressing machines and for card index systems; and has special reference to the provision of a stencil plate and index card constructed and adapted to permit convenient manipulation and handling during the cutting of the type characters on the stencil and to provide an index and printing plate efficiently serviceable during card indexing and addressing use.

One of the principal objects of my present invention comprehends the provision of a stencil or address plate possessing the characteristics of sufficient rigidity to afford a stable, strong and durable structure for indexing purposes, of suitable thickness to permit of proper mechanical feeding through an addressing machine and of sufficient flexibility and pliability to afford or permit the facile cutting of the stencil in an ordinary typewriter without the employment of the usual plate receiving attachments. A well-known form of stencil plate for addressing machines comprises a fibre or board body or frame provided with an orifice or window over which is affixed a stencil sheet, the latter being adapted to be cut with the desired type characters in an ordinary typewriter. A stencil plate of this kind is desirably made relatively rigid and thick to the end of providing a structure having sufficient "body" capable of standing upright in an index drawer or file and capable of withstanding the rough service to which it is subjected during indexing and addressing machine use. A disadvantage in this prior form of stencil plate resides in the fact that the frame or plate is not flexible and pliable enough to be received between the feed rollers of a typewriter machine without mutilating or otherwise rendering the same unfit for use, it being the practice in cutting a stencil in a typewriter to mount stencil-supporting attachments on the typewriter, the employment of such attachments being attended in practice with various difficulties. To

eliminate the disadvantages inherent in and incident to the use of these prior stencil plates, my present invention comprehends the provision of a stencil plate construction which, although of sufficient rigidity, stiffness and "body" to efficiently "stand up" during card-indexing and addressing machine use, is constructed to provide sufficient flexibility and yieldability for insertion in the ordinary typewriter for cutting of the stencil.

Another principal object of my present invention relates to the provision of a stencil plate which may be interchangeably employed as a record card and as a guide or index card during indexing use, the plate being so constructed that any changes in the indexing system may be made with extreme rapidity, ease and convenience in accordance with the changes from time to time of the index or mailing list. Where a mailing list is to be kept always "up-to-date," it is of great importance that the indexing of the address plates should be capable of being changed in a simple manner and with rapidity and convenience. To permit rapid changes in indexing each stencil plate of my invention is constructed to be readily adaptable for serving as a guide or index card, the stencil being constructed to readily receive removable index or guide tabs, the construction provided being, furthermore, such that the stencil plate with or without the index tab thereon offers no undesirable surface or edge projections as is the case in prior constructions, a perfectly flat plate or frame without upstanding tabs being thereby provided with the plate thus capable of rendering sufficient service as an index card.

The principal objects of my present invention may be said to include, besides the provision of an address plate and index card having the characteristics and yielding the results above mentioned, the further provision of a laminated plate or index card having a plurality of layers or plies obtained from a blank of flexible sheet material, the latter being adapted for easy insertion in an ordinary typewriter for stencil cutting, the blank after stencil-cutting operation being folded into laminated formation with the layers or laminations united and forming a rigid and strong stencil plate or card; the further provision of a

card or stencil plate of this nature in which the frame of the stencil may be provided with an easily legible record of the stencil data, the said record being made to appear 5 on the face of the stencil and being obtained concomitantly with the cutting of the stencil; the further provision of a stencil plate or index card in which the laminations or plies are so united as to provide a tab-re- 10 ceiving valley or channel between the laminations at an edge thereof, the said channel being intended for removably receiving guide or index tabs without effecting a structure having any undesirable edge or 15 surface projections on the card or plate; the further provision of a blank adapted to be folded for providing the laminated stencil card and the still further provision of a plate or card of the nature referred to 20 provided with means adapted to cooperate with feeding implements in the addressing machine for efficiently feeding the stencil plates through the addressing machine without incurring the disadvantages inher- 25 ent in prior feeding methods.

To the accomplishment of the foregoing and such other objects as may hereafter appear, my invention consists in the elements and their relation one to the other, 30 as hereinafter particularly described and sought to be defined in the claims, reference being had to the accompanying drawings which show preferred embodiments of my invention, and in which:

35 Figure 1 is a perspective view showing my stencil plates arranged in stack formation in an index file or drawer,

Figure 2 is a view of a blank from which the stencil plate is formed,

40 Figure 3 is a view of the same showing the manner of cutting the stencil,

Figure 4 is a view of the blank showing the manner of folding the same into stencil plate frame formation,

45 Figure 5 is a cross sectional view of the same taken on the line 5—5, Figure 6,

Figure 6 is a face view of the plate showing the manner in which the same is adapted for receiving removable index or guide tabs,

50 Figure 7 is a view showing a modification of the stencil plate blank,

Figure 8 is a view of the same folded into stencil plate formation, and

55 Figure 9 is a view of a still further modification showing an ordinary index card made in accordance with the principles of my invention.

As hereinbefore indicated, a principal object of my present invention comprehends the provision of an index plate or stencil constructed to be readily insertible in the rollers of an ordinary typewriter for cutting the stencil and constructed to provide a rigid, 60 strong and durable stencil plate. To these

ends I have found it desirable to provide a laminated stencil frame or plate made from a blank of flexible sheet material, the blank having the desired characteristics of flexibility and yieldability for insertion in a 70 typewriter, the said flexible blank being adapted to be folded into stencil plate formation. Referring to Figure 2 of the drawings, the blank which I prefer to use may comprise a sheet of flexible material A made of paper, cardboard, fibre or the like, the said blank being cut or shaped to provide the end sections a' and a^2 and an intermediate section a^3 , the section a^2 being adapted to be folded about the scoring line s' to overlie 75 the section a^3 , the section a' being in turn intended for being folded over the section a^2 about the scoring line s^2 . Where the frame is to be used as a stencil plate, each section a' , a^2 and a^3 is provided with an orifice of 80 suitable preferably rectangular form, the section a' being provided with the orifice o' , the section a^2 with the orifice o^2 and the section a^3 with the orifice o^3 , these orifices being so cut in the respective sections as to register 85 with one another when the sections are folded into overlying or superposed relation. One of the orifices may be covered with a stencil sheet such as a stencil fabric and in the present form of my construction the orifice o^3 is so covered with a stencil sheet S, the latter being affixed to the section a^3 as by being pasted thereover. Although I prefer to provide three sections a' , a^2 and a^3 , it will 90 be apparent that any number of sections may be provided such, for example, as the two sections a' and a^3 , the section a^2 being preferably employed for a further purpose, as will appear hereinafter.

For cutting the type characters in the stencil sheet S the flexible blank A is intended to be folded and inserted between the rollers of an ordinary typewriter and to this end the said blank A may be scored as at b, the scoring b being such as to permit backward 105 folding of the section a' beneath the section a^3 . This is shown, for example, in Figure 3 of the drawings, in which the top section a' is folded underneath the stencil section a^3 and the thus folded blank inserted in 110 an ordinary typewriter for cutting the type characters on the stencil S. With the provision of this construction the underneath section a' forms a suitable backing for the stencil sheet S during the cutting of the same, 115 as will be clear from a consideration of Figure 3, this arrangement further permitting the recording of the data of the stencil on the section a' concomitantly with the cutting of the type characters on the stencil S. A 120 desideratum of the invention, as hereinbefore mentioned, comprehends a stencil structure in which the obverse face or side of the final stencil plate may be provided with the 125 legible data of the stencil itself, with the 130

data preferably recorded adjacent the upper edge of the stencil plate. This is obtained by the folding of the blank into the formation shown in Figure 3, the face f of the section a' , which is adjacent to the stencil sheet S during the cutting of the latter, forming the obverse side or face of the final stencil plate. It will thus be seen that if during stencil cutting, a carbon sheet is inserted between the sections a' and a^3 , the cutting of the type characters on the stencil sheet S will effect the simultaneous recording of the desired data on the face f of the section a' , the desired record data appearing on the face of the card adjacent its upper edge, as clearly shown at r in Figures 1 and 6 of the drawings.

After the cutting of the stencil on the flexible blank and the transfer of the data thereon on the obverse face of the section a' of the blank, the blank is folded to provide a laminated and rigid stencil plate. This is shown particularly in Figure 4 of the drawings, and referring now to this figure, it will be seen that the section a^2 has been folded to overlie the section a^3 ; the section a' being shown here in the process of being folded to overlie the combined sections a^2 and a^3 . These sections in the finished plate form a plurality of plies or layers which are adhesively connected together to provide the desired frame. For suitably attaching the plies together the section a^2 may be provided on its opposite faces f' and f^2 with an adhesive material, these faces being preferably gummed so that when the blank is folded into the desired configuration the opposite faces f' and f^2 of the section a^2 may be suitably moistened and affixed to the adjacent faces of the sections or plies a' and a^3 , the resulting laminated plate generally designated as L being clearly shown in Figures 1, 5 and 6 of the drawings.

As heretofore referred to, another principal object of my present invention relates to the production of a stencil plate which is adapted for interchangeable use as an ordinary card and as an index or guide card, each stencil plate being constructed to detachably receive index or guide tabs in a quick and convenient manner. To the accomplishment of these ends the sections or laminations of the plate are so united as to leave ununited or free walls of the plies adjacent the top edge of the plate, the said ununited wall portions defining a valley or channel for the reception of a removable index tab. In the preferred construction, to attain this end the intermediate section or ply a^2 is provided with portions of less height or width than the exterior layers or sections a' and a^3 , the ply a^2 being preferably shaped so that the top edge e^2 thereof is spaced a distance from the folded edge of the sec-

tions a' and a^3 provided by the scoring line s^2 . With the provision of this structure, when the layers or plies are united together throughout the area of the section a^2 the contiguous or adjacent wall portions of the sections a' and a^3 at the upper or folded edge thereof are free and ununited, the said walls being, furthermore, spaced apart by the interposition of the section or ply a^2 , a free transverse channel or valley v being thereby provided, the construction being such that the top edge e^2 and the scored edge s^2 provide limiting abutments for properly positioning and holding an index tab freely insertible in the valley v . This is clearly shown in Figures 1 and 6 of the drawings, and referring to these figures, it will be seen that one or more index tabs such as t and t' may be removably inserted as at opposite sides of the stencil plate. For exposing these guide or index tabs to view the top edge of the laminated plate is suitably notched to provide exposure openings and to this end the stencil blank A may be initially provided with cut-out portions such as c and c' arranged at the scoring line s^2 such that when the section a' is folded over the section a^3 the cut-out portions c and c' will define the exposure openings for the index tabs t and t' , this being clearly shown in Figures 1 and 6 of the drawings.

In the prior use of stencil plates in addressing machines the plates are fed to the point of imprint by being pushed or drawn from the magazine, the feeding of the advance plates being dependent upon the feeding of subsequent plates, this method of feeding resulting in considerable clogging and jamming of the plates in the addressing machine. To eliminate this disadvantage I prefer to provide in the stencil plate of my construction cut-out portions to serve as feeding notches adapted for cooperation with moving pawls effective to individually feed each of the stencil plates independent of the others, undesirable clogging and jamming being thereby obviated. To this end each of the sections a' , a^2 and a^3 is provided with complementary cut-out portions in the side edges thereof such as d and d' , all the cut-out portions d being adapted for registration in the laminated plate L , the registered cut-out portions defining feeding notches adapted for the before-mentioned cooperation with feeding pawls. These notches d and d' are preferably situated so as to be decentrally located in the plate, feeding of the plate being thereby facilitated. With this method of feeding I am further enabled to make the stencils of much thinner material, the provision of thick stencils having been previously in part made necessary by the limitations of the feeding methods employed in the addressing

4
machine. With my construction, therefore, thinner stencils may be employed, thereby further enabling more of the stencils to be filed or stored in a given space.

5 Where the record or data adjacent the upper edge of the plate is not desired, the stencil plate may be made of smaller dimensions as shown in Figures 7 and 8 of the drawings. Referring to these figures, the
10 blank A' may be made to provide the sections a⁴, a⁵ and a⁶, these sections being of smaller dimensions than the corresponding sections of the blank A shown in Figure 2, these sections being provided with the ori-
15 fices or windows o⁴, o⁵ and o⁶, the window o⁶ being covered by the stencil sheet S', the latter being affixed to the section a⁶ as by being glued or pasted thereto. The blank may be scored as at s³ and s⁴ to facilitate folding of
20 the blank into the laminated plate formation L'. The blank may be also provided with the cut-out portions c² and c³ for defining the exposure notches in the top edge of the plate. In lieu of providing the section a⁵
25 with the gumming material on its opposite faces thereof, all the sections a⁴, a⁵ and a⁶ may be suitably gummed, leaving, however, the contiguous wall portions of the sections a⁴ and a⁵ adjacent the scoring line s⁴ clear
30 and ungummed to permit the obtaining of the free channel v' in the resulting plate formation, as shown in Figure 8 of the drawings.

35 The principles embodied in my stencil plate may be employed for ordinary index cards where it is desired to provide a card interchangeably utilizable for record and indexing purposes. Such a card is shown in Figure 9 of the drawings and referring to
40 this figure the card L² comprises the three laminations or plies a⁷, a⁸ and a⁹ united together in a manner similar to the attaching of the sections in the stencil plate heretofore detailed, the intermediate ply a⁸ being of
45 lesser dimensions than the exterior plies a⁹ and a⁷, this to the end of providing the free and unobstructed channel v². The card may be suitably notched as at c⁴ and c⁵ to provide the exposure openings for the index tabs,
50 these notches being obtained by cutting out suitable portions in the blank from which the index card is made.

55 The manner of making and using my stencil plate and index card will, in the main, be apparent from the above detailed description thereof. The plates may be sold and distributed to the trade in the blank form as shown in Figure 2 of the drawings, the said blank consisting of a flexible and pli-
60 able sheet A having the desired cut-out portions and notches therein. For cutting or perforating the stencil, the section a' is folded over the scored line b underneath the section a³, a suitable backing for the stencil sheet S being thus provided; and the section
65

a' receives during stencil cutting an imprint for obtaining a legible record on the obverse side of the resulting laminated plate, all as shown in Figures 1, 3 and 6 of the drawings. After cutting of the stencil the sections or plies a', a² and a³ are folded over the lines s' and s² and the sections or plies are united to effect the provision of the laminated plate L shown in Figures 1, 5 and 6 of the drawings. The parts are so relatively arranged and contoured as to provide a free channel v at the upper edge of the plate for the removable reception of index tabs or guides. With this construction it will be seen that I may provide a laminated card or plate which is strong, rigid and durable while at the same time providing a flexible construction adapted for simple and easy insertion in an ordinary typewriter during stencil cutting. It will be further seen that I have provided a card for interchangeable use wherein the index tabs may be quickly inserted and removed from time to time as the needs of service require, the stencil plates being constructed for receiving removable index tabs without producing surface or edge projections in the plates, as is the case in prior constructions, the plate being perfectly flat on both sides thereof and no projecting portions being provided at the top edges of the plates, the top wall of a stack formation as shown in Figure 1 of the drawings being perfectly smooth and flat, thus eliminating tearable and mutilatable projecting tabs incident to prior structures of this type. It will be
100 further understood that by the provision of the feeding notches I am enabled to feed the stencil plates with considerable facility in the addressing machine. My stencil plate and index card thus is made to combine characteristics desirable in all of its uses, first for stencil cutting, then for indexing purposes and lastly for utilization in addressing machines.

105 While I have shown my device in the preferred form, it will be obvious that many changes and modifications may be made in the structure disclosed without departing from the spirit of the invention, defined in the following claims.

110 I claim:

115 1. As a new article of manufacture, a laminated address plate or frame made of flexible sheet material and folded to provide a plurality of layers or plies, the said layers being united with contiguous wall portions of the layers at an edge of the plate left ununited or free for defining or providing a channel or valley adapted for the reception of a removable index or guide tab.

120 2. As a new article of manufacture, a laminated plate or frame made of flexible sheet material and folded to provide a plurality of layers or plies, the said layers be-

ing united with contiguous wall portions of the layers at an edge of the plate left ununited or free for defining or providing a channel or valley adapted for the reception of a removable index or guide tab, the said edge of the plate being provided with an exposure notch for the said index or guide tab.

3. As a new article of manufacture, a laminated stencil plate or frame comprising a plurality of layers or plies of sheet material united with contiguous wall portions at an edge of the plate left free and defining a tab-receiving and positioning channel or valley.

4. As a new article of manufacture, a laminated stencil plate or frame comprising a plurality of layers or plies of sheet material united, with contiguous wall portions at an edge of the plate left free and defining a tab-receiving and positioning channel or valley, the said edge being provided with cut-out portions for exposing the tabs.

5. As a new article of manufacture, a laminated plate or frame made of a single blank of flexible sheet material and folded to provide a plurality of layers or plies, the said layers being united with contiguous wall portions of the layers at the folded edge of the plate left ununited or free for defining an index tab receiving channel or valley.

6. As a new article of manufacture, a laminated address plate or frame made of flexible sheet material and folded to provide a plurality of layers or plies, the said sheet material being orificed to provide when folded into plate formation an exposure notch in an edge thereof, the said layers of the plate being united with contiguous wall portions of the layers at the said edge of the plate left ununited or free for providing an index tab receiving channel.

7. As a new article of manufacture, a laminated stencil plate or frame comprising a plurality of layers or plies of sheet material provided with registering orifices and a stencil sheet thereover, the said layers being united with contiguous wall portions at an edge of the plate left ununited and defining a tab-receiving and positioning channel or valley.

8. As a new article of manufacture, a blank adapted to be folded for providing a laminated plate or frame, the said blank being provided with a plurality of wing sections adapted to be folded into overlying relation, the blank being provided with a cut-out portion between the said sections adapted upon folding of the blank to provide a tab exposure notch in an edge of the plate.

9. As a new article of manufacture, a blank adapted to be folded for providing a

laminated plate or frame, the said blank being provided with a plurality of wing sections adapted to be folded into overlying relation, the blank being provided with a cut-out portion between the said sections adapted upon folding of the blank to provide a tab exposure notch in an edge of the plate, the overlying wing sections being orificed with the orifices arranged to register in the folded blank and a stencil sheet covering one of the orifices.

10. As a new article of manufacture, a laminated plate or frame made of sheet material and folded to provide a plurality of united layers or plies, the said layers including exterior plies and an intermediate ply, an edge portion of the intermediate ply being spaced from a folded edge of the exterior plies, the space therebetween defining a tab-receiving valley or channel, the folded edge of the exterior plies and the edge portion of the intermediate ply forming limiting abutments for the said valley.

11. As a new article of manufacture, a laminated address plate or frame made of sheet material and including a plurality of united layers or plies, the said layers comprising exterior plies, and an intermediate ply spaced from adjacent edges of the exterior plies, the space therebetween defining a tab-receiving valley or channel having spaced walls.

12. As a new article of manufacture, a laminated plate or frame made of sheet material and folded to provide a plurality of united layers or plies, the said layers including exterior plies and an intermediate ply, an edge portion of the intermediate ply being spaced from a folded edge of the exterior plies, the space therebetween defining a tab-receiving valley or channel, the folded edge of the exterior plies and the edge portion of the intermediate ply forming limiting abutments for the said valley, the said folded edge of the exterior plies being cut to provide a tab exposure notch.

13. As a new article of manufacture, a laminated plate or frame made of sheet material and including a plurality of united layers or plies, the said layers comprising exterior plies and an intermediate ply, an edge portion of the intermediate ply being spaced from the adjacent edges of the exterior plies, the space therebetween defining a tab-receiving valley or channel, the said plies being provided with registering orifices or windows and a stencil plate affixed thereover.

14. As a new article of manufacture, a blank adapted to be folded to provide a laminated plate or frame, the said blank including an intermediate section and two end sections, the end sections being adapted to be folded into overlying relation with respect to the intermediate section with one

- of the end sections having portions of lesser width than the other whereby, when the sections are folded and united, a plate having a channel in an edge thereof is provided.
15. As a new article of manufacture, a blank adapted to be folded to provide a laminated plate or frame, the said blank including an intermediate section and two end sections, the said sections being provided with orifices adapted to register when the blank is folded, one of the orifices being covered with a stencil sheet, the end sections being adapted to be folded into overlying relation with respect to the intermediate section, one of the end sections being of lesser width than the other whereby when the sections are folded and united, a plate having a channel in an edge thereof is provided.
16. As a new article of manufacture, a blank adapted to be folded to provide a laminated plate or frame, the said blank including an intermediate section and two end sections, the end sections being adapted to be folded into overlying relation with respect to the intermediate section, one of the end sections being of lesser width than the other whereby when the sections are folded and united, a plate having a channel in an edge thereof is provided, the said end section of lesser width being coated on its opposite faces with adhesive material.
17. As a new article of manufacture, a blank of sheet material including two sections each provided with an orifice and adapted when folded for forming a stencil frame with the orifices in registration, a stencil sheet over one of said orifices, the said blank being scored for reverse folding whereby one of the sections is adapted to form a backing sheet for the other section and arranged to underlie the stencil sheet thereon during cutting of the stencil.
18. As a new article of manufacture, a blank of sheet material including two sections each provided with an orifice and adapted when folded for forming a stencil frame with the orifices in registration, a stencil sheet over one of said orifices, the said blank being provided with a cut-out portion forming an exposure notch in the folded blank, the said blank being scored for reverse folding whereby one of the sections is adapted to form a backing sheet for the other section and arranged to underlie the stencil sheet thereon during cutting of the stencil.
19. As a new article of manufacture, a blank of flexible sheet material including two sections adapted to be folded into overlying relation, the sections adapted for forming the obverse and reverse sides of a stencil plate, one of the sections being provided with an orifice or window and a stencil sheet affixed thereover, the blank being scored for folding one of the sections underneath the other during cutting of the stencil whereby the data cut upon the stencil may be copied upon the said underneath section, the construction being such that the copied data appears on the obverse side of the finally folded stencil plate.
20. As a new article of manufacture, a blank of sheet material comprising two end sections and an intermediate section each provided with an orifice and adapted when folded for forming a stencil frame with the orifices in registration, a stencil sheet over one of said orifices, the said blank being scored for reverse folding whereby one of the sections is adapted to form a backing sheet for the stencil section during cutting of the stencil, one of the said sections being of less width than the other.
21. As a new article of manufacture, a laminated plate or frame made of sheet material folded to provide a plurality of layers or plies, said sheet material being provided with a plurality of orifices arranged to register in the folded plate and with an orifice for providing in an edge of the folded plate an exposure notch for an index tab.
22. As a new article of manufacture, a laminated address plate or frame made of sheet material including spaced exterior layers or plies and an intermediate layer or ply, the said intermediate ply being spaced from the adjacent edges of the exterior plies with the space defining a tab receiving valley or channel, and an orifice in said exterior plies defining an exposure notch for an index tab.
- Signed at New York city, in the county of New York and State of New York, this 12th day of April, A. D. 1922.
- CHAS. E. ELLIS.
